ELECTROMAGNETIC COUNTER UNIT

Benjamin Cooper, New York, N. Y.

Application January 4, 1937, Serial No. 118,970

8 Claims. (Cl. 175—337)

This invention relates to electromagnetic counter units and supports therefor.

An object of this invention is to provide a unit of the character described, comprising a pair of electromagnets on a common frame for actuating separate sets of figured wheels mounted on a single shaft supported by the frame, the magnets being so arranged as to make for a compact and rugged construction.

10 A further object of this invention is to provide a unit and support of the character described, including highly improved means for removably mounting the unit on the support, to permit quick replacement of units on said support.

15 Another object of this invention is to provide in an electromagnetic unit of the character described, highly improved pawl and ratchet means, including a coil spring for maintaining a pawl member in engagement with the teeth of the 20 ratchet and adapted to be compressed during operation of the unit.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

30 In the accompanying drawing, in which is shown one of the various possible illustrative embodiments of this invention,

Fig. 1 is a side elevational view of an electromagnetic counter unit embodying the invention and mounting therefor;

Fig. 2 is a top plan view of the structure shown in Fig. 1;

Fig. 3 is a cross-sectional view taken on line 3—3 of Fig. 1;

40 Fig. 4 is a cross-sectional view taken on line 4—4 of Fig. 1;

Fig. 5 is a cross-sectional view taken on line 5—5 of Fig. 1; and

Fig. 6 is an enlarged side elevational view of the improved pawl and ratchet mechanism.

45 Referring now in detail to the drawing, 10 designates an electromagnetic counter unit embodying the invention and 11 designates an improved support for said unit. A part only of the support 11 is shown on the drawing, the support being elongated and contracted to support a plurality or bank of units 10 disposed side by side. Said support comprises a horizontally extending plate 12 disposed in a vertical plane formed 50 with a horizontal through opening 13. The same

may also be formed with a vertical screw-threaded opening 14 communicating with opening 13 and having a countersunk portion 15 at the top.

5 Fixed to the member 12 are a plurality of horizontal pins 16 and 17 arranged above and below the opening 13 and on opposite sides thereof. The pins 16 and 17 project beyond the front surface 19 of the member 12. Fixed to the top of the member 12 is a horizontal insulating plate 10 20, having an opening 21 registering with the countersunk opening 15. Attached to the insulating plate 20 are a plurality of spade terminals 22, to which wiring 22a may be fixed.

25 Within the threaded opening 14 is a screw 23 having a tapered lower end portion 24. The screw 23 is of such length that when fully screwed down within the opening the lower tapered end 24 thereof will project into the opening 13 and the head thereof into countersunk portion 15. 20

30 The unit 10 comprises a frame 25 having a vertical wall portion 26 and a horizontal wall portion 27, welded or otherwise permanently secured thereto. Fixed to the top of the frame and at substantially the level of plate 20, is a 25 horizontal plate 28 formed with a plurality of through openings 29, for the purpose hereinafter appearing. There is also fixed to the rear wall 26, a jack pin 30, received within the opening 13. The pin 30 is formed at the top thereof with a 30 tapered opening 32 to receive the lower tapered end 24 of the screw 23. Said rear wall 26 of the frame is also formed with a pair of openings 34 to receive the pins 16 and 17 of the support.

35 Thus, to mount the frame on the support 12, 35 the jack pin 30 is inserted in the opening 13 in the support 12, and the screw 23 thereafter screwed down, whereby the tapered end 24 thereof engages the tapered opening 32 of said pin to draw the pin inwardly within the openings for 40 firmly securing the frame to the support. The tapered or conical opening 32 may be somewhat larger than the tapered or conical screw end 24, as shown in exaggeration in Fig. 1 of the drawing.

45 Extending from the wall 26 are a pair of parallel vertical wall portions or flanges 40 provided with aligned openings 41 below horizontal wall 27, supporting a shaft 42. On said shaft 42 is a set of counter wheels 43 controlled by a 50 ratchet 44 disposed between walls 40, and a second pair of counter wheels 45 controlled by a ratchet wheel 46 disposed adjacent one of said walls 40. The counter wheels may be geared together through suitable gearing 47 on the shaft 55

48 likewise supported by and between the walls 40 of the frame. Supported by the frame walls 40 is a shaft 50, on which are mounted a pair of levers 51 aligned with and engaging the 5 ratchets 44 and 46 to prevent retrograde movement thereof. Levers 51 may be held against the ratchets by springs 52 interposed between the upper ends of said levers and integral tab extensions 54 at the rear end of a horizontal wall 10 27 of the frame.

The rear end of the horizontal wall 27 of the frame is received between the parallel walls 40 and extends forwardly therefrom. Said wall is formed with downwardly extending flanges 27a, 15 27b. One flange 27a of said wall 27 is substantially straight. The other flange 27b of said wall is stepped, said wall being widest between walls 40, narrower as at 55 in front of walls 40 and narrowest at its outer end as at 56. Said 20 horizontal wall is formed with a pair of offset through openings 60 and 61, the former being closer to the straight flange 27a of the horizontal frame wall 27.

Mounted on the horizontal wall 27 of the frame 25 25 are a pair of similar partial housings or supports 62 and 63 for electro-magnets 64 and 65. The support or partial housing 62 comprises a bottom wall 66 and upstanding walls 67 and 68 parallel to the vertical wall 26 of the frame. The 30 bottom wall 66 has a central opening 69 co-axial with the opening 61. Extending through said openings 61, 69 is a reduced screw-threaded stem 70 on the core 71 of the electro-magnet 64. A nut 75 screwed to the stem 70 and disposed in 35 opening 61, serves to fix the electro-magnet on its support. A pair of screws 76 on opposite sides of the opening 61 serve to screw the bottom wall 66 of the support 62 to the frame wall 27.

Extending from the upper end of the wall 67 40 are a pair of parallel horizontal arms 77 disposed on opposite sides and adjacent the upper end of the electro-magnet 64. The arms 77 are interconnected by a horizontal shaft 78 parallel to the wall 67. The wall 68 is shorter than the wall 67 45 and fixed thereto is a plate 80 having a pair of spaced, slotted ears 81 at the upper end thereof engaging the shaft 78. The support 62, as shown in the drawing, is spaced from the edge adjacent straight flange 27a of the frame wall 27, one side 50 of said support being substantially flush with the inwardly stepped portion 55 of the frame wall.

The support 63 is substantially similar in construction to the support 62 and likewise comprises a bottom wall 66a and upstanding vertical walls 55 67a and 68a. The support is attached to the wall 27 by screws 76a and the bottom wall 66a thereof has a central opening 69a co-axial with the opening 60 and receiving therethrough the stem 70a of the core 71a for the electro-magnet 65. A nut 75a disposed within the opening 60 and screwed to the stem 70a serves to fix the electromagnet 65 on its support 63. The upstanding wall 67a likewise has a pair of parallel horizontal arms 77a on opposite sides of the upper end of the electro-magnet 65. The said arms 77a are interconnected by shaft 78a. Fixed to the wall 68a is a plate 80a having slotted hooks or ears 81a engaging the shaft 78a. The support 63, as shown in 60 Fig. 2 of the drawing, is offset with respect to the support 62 being closer to the straight side 27a of the frame wall 27. It will be noted that the support 63 substantially overlies the narrow end portion of the frame.

Pivoted on the shaft 78 is a bell crank 85 having a substantially flat horizontal armature arm

86 overlying the upper end of the magnet 64. The lever 85 has a pair of apertured ears 87 receiving the shaft 78 therethrough. Said bell crank lever 85 furthermore has a downwardly extending arm 89 disposed in a plane perpendicular to the frame wall 27 and vertical frame wall 26. The arm 89 extends below the frame wall 27 and adjacent the stepped portion 55 of said frame wall. Thus, although the arm 89 is spaced from the stepped portion 55 of the wall 27, it nevertheless does not project beyond the adjacent vertical frame wall 40. The bell crank 85 is furthermore formed on the side thereof, opposite to the arm 89, with an ear 90 connected to the support wall 67 by a coil tension spring 91.

Mounted on the wall 80 is an insulating block 92 supporting a plurality of spring contacts 93. On the arm 89 is an insulating button 94 adapted to engage one of said spring contacts to move the same relative to the others when the magnet 64 is energized. The lower end of arm 89 of said bell crank 85 is connected to pawl mechanism 100 for actuating the ratchet 46.

The pawl mechanism 100 comprises a swing plate 101 pivoted on shaft 42 adjacent one side of ratchet 46, and interconnected by link 89b to the arm 89. Pivoted on the swing plate 101 and contacting a side face thereof, and disposed in the plane of ratchet 46, is a small bell crank pawl lever 102 having a tooth 103 engaging within a notch 104 of the ratchet 46. The other arm 107 of the pawl lever 102 is bent at an angle into the plane of the plate 101. Said plate 101 is provided with an arm 109 carrying a fixed cup 110 spaced from and aligned with arm 107. On the arm 107 30 is a fixed pin 111 aligned with the cup 110. A coil compression spring 112 has one end received within the cup 110 and receives at its other end, said pin 111.

When the electro-magnet 64 is deenergized, the 40 spring 91 pulls the bell crank 85 in a counterclockwise direction, looking at Fig. 1 of the drawing, and causing the plate 101 to be rotated on its axis in a clockwise direction, looking at Figs. 1 and 6 of the drawing. In this position the tooth 45 or arm 103 of the pawl lever 102 will be disposed within the notch 104 of the ratchet 46 engaging a tooth of said ratchet.

A jam member 114 mounted on and between the walls 40 serves to retain the pawl and ratchet in the position shown in Fig. 6 of the drawing and to prevent overthrow. When the electromagnet 64 is energized, however, the bell crank lever 85 will be rotated in a clockwise direction to cause rotation of the swing plate 101 in a counter clockwise direction. During this movement the tooth 103 will slide on the ratchet tooth causing the pawl lever 102 to rotate in a counterclockwise direction about its pivot, looking at Fig. 6 of the drawing, and causing compression of the spring 60 112. However, when the tooth 103 clears the ratchet tooth, it will drop into the next notch 104 under action of compressed spring 112. When the electromagnet is deenergized, the bell crank moves in an opposite direction under the influence of spring 91, causing the pawl or lever 102 to rotate the ratchet about the axis of shaft 42.

On shaft 78a is a bell crank lever 85a similar to the bell crank lever 85 and likewise having an armature arm overlying the upper end of the magnet 65 and an ear 90a connected to the wall 67a by coil tension spring 91a. The bell crank lever 85a likewise has an arm 89a extending below the wall 27 and disposed in a plane parallel to the plane of arm 89. The arm 89a, however, is offset with 75

respect to the arm 89 being disposed adjacent the stepped narrow end 56 of the frame wall 27. On wall 80a is also an insulating block carrying a plurality of spring contacts adapted to be actuated by a button on the arm 89a.

5 To actuate the ratchet wheel 44, there is provided pawl mechanism similar to the pawl mechanism 100 including a swing plate pivoted about the axis of the shaft 42 and connected to the lower end of the arm 89a by a link 115. The link 115 is disposed parallel to the link 89b and beneath the wall 27. The lower end of the arm 89a may be bent inwardly toward the flange 27a and connected to the link by a pin 116 carrying a 15 spacer sleeve 117.

The wiring 120 for the electromagnets may extend between the wall 67 of the support 62 and the wall 26 of the frame 25 and pass through the openings 29 of the insulating plate 28. Terminals 121 at the ends of the wires 120 are adapted for quick or detachable connection to the spade terminals 22. Thus, if it is desired to remove the unit 10, it is merely necessary to disconnect the terminals 121, 22 and remove the screw 23 permitting the unit to be pulled away from the support 12. It will now be understood that where a plurality of units 10 are mounted in a bank on a common support 12, they may be quickly replaced.

30 The units, furthermore, are compact whereby a relatively large number of such units may be mounted in a relatively small space. It will be noted, furthermore, that the electromagnets 64, 65 are mounted on the same frame adjacent one another and operate different sets of counter wheels disposed on the same shaft supported by said frame, thus making for a compact and rugged construction. In the pawl mechanism 100, the compression spring 112 which retains the pawl in engagement with the ratchet tooth will 35 withstand considerable use without fatigue, and eliminates the usual strip spring which is normally subjected to bending and frictional contact.

40 It will be noted that after the arm 89 has moved forwardly to rotate the ratchet 46, the pawl mechanism will be in the position shown in Fig. 6 of the drawing. In such position the outer edge of the pawl tooth 103 is in a vertical line passing through the axis of the shaft 42 and contacts the radial edge of a tooth of the ratchet. The bottom edge of the pawl tooth 103 is at right angles to a vertical line passing through the axis of the shaft 42 and contacts an edge of the next adjacent tooth and is in alignment with the axis of the pawl 102.

45 It will be noted, furthermore, that the angle defined by lines passing through the axis of the shaft 42 and the axis of the pivotal connection between the link 89b and the plate 101 at the beginning of the ratchet actuating stroke, as shown in Fig. 1, and at the end of the actuating stroke, as shown in Fig. 6, is bisected by a vertical line passing through the axis of the shaft 42. With such construction a maximum efficiency and driving force for the pawl mechanism is obtained.

50 It will thus be seen that there is provided a device in which the several objects of this invention are achieved, and which is well adapted to meet the conditions of practical use.

70 As various possible embodiments might be made of the above invention, and as various changes might be made in the embodiment above set forth, it is to be understood that all matter herein set forth or shown in the accompanying drawing is

75 to be interpreted as illustrative and not in a limiting sense.

Having thus described my invention, I claim as new my desire to secure by Letters Patent:

1. An electromagnetic unit comprising a frame, a pair of parallel, vertical electromagnets mounted thereon, a horizontal shaft on said frame and below the lower ends of said electromagnets, a pair of ratchets on said shaft, bell cranks pivoted on said frame having armatures overlying the upper ends of said electromagnets, and arms extending downwardly beneath the electromagnets, pawl mechanisms for actuating said ratchets and links connecting said mechanisms to said arms, said electromagnets overlapping one another longitudinally and perpendicularly of said shaft, whereby said electromagnets are disposed at different perpendicular distances from said shaft, and the axes of said electromagnets are in spaced vertical planes perpendicular to said shaft, and said links being horizontal and parallel to one another, and the link for the electromagnet further from the shaft being longer than the other link and disposed directly beneath the other electromagnet.

2. An electromagnetic unit comprising a frame, a pair of parallel, vertical electromagnets mounted thereon, a horizontal shaft on said frame and below said magnets, a pair of ratchets on said shaft, bell cranks pivoted on said frame having armatures overlying the upper ends of said electromagnets, and downwardly extending arms, and pawl mechanisms for actuating said ratchets and connected to said arms, said electromagnets being offset from one another and overlapping longitudinally and perpendicularly of said shaft, said arms being in spaced parallel planes perpendicular to said shaft, one of said pawl mechanisms being connected to the arm of the bell crank for the electromagnet furthest from the shaft by a link disposed below the other electromagnet.

3. An electromagnetic unit, comprising a frame having a horizontal wall, a vertical wall at right angles to said horizontal wall, and a pair of parallel vertical flanges at right angles to said horizontal and vertical walls, a horizontal shaft supported by said flanges and disposed beneath said horizontal wall, a pair of spaced ratchets on said shaft, a pair of parallel vertical electromagnets on said horizontal wall of the frame, and means controlled by said magnets for actuating said ratchets, the axes of said electromagnets being disposed in spaced parallel planes perpendicular to said shaft, and at different distances from said shaft, the axis of one of said electromagnets being disposed between said shaft and said other electromagnet.

4. An electromagnetic unit comprising a frame having a horizontal wall, a vertical wall extending upwardly above said horizontal wall and at right angles thereto, and a pair of parallel vertical flanges disposed at right angles to said horizontal and vertical walls, a horizontal shaft supported on and between said flanges below said horizontal wall, a pair of spaced ratchets on said shaft, a pair of U-shaped members on said horizontal wall, each having a bottom wall contacting said horizontal wall and a pair of upstanding walls, a vertical electromagnet on each member between the upstanding walls thereof, and means pivoted on said members and controlled by said magnets for actuating said ratchets.

5. An electromagnetic unit comprising a frame having a horizontal wall, a vertical wall extending upwardly above said horizontal wall and at

right angles thereto, and a pair of parallel vertical flanges disposed at right angles to said horizontal and vertical walls, a horizontal shaft supported on and between said flanges below said horizontal wall, a pair of spaced ratchets on said shaft, a pair of U-shaped members on said horizontal wall, each having a bottom wall contacting said horizontal wall and a pair of upstanding walls, a vertical electromagnet on each member between the upstanding walls thereof, and means pivoted on said members and controlled by said magnets for actuating said ratchets, one of said electromagnets being closer to the vertical wall than the other, and said electromagnets being offset one from the other.

6. An electromagnetic unit comprising a frame having a wall and supporting a shaft below said wall and parallel thereto, a pair of electromagnets on said wall perpendicular to said wall, the axes of said electromagnets being disposed in spaced parallel planes perpendicular to said shaft and in spaced parallel planes parallel to said shaft, one of said magnets lying mainly between the other magnet and a plane passing through the shaft and perpendicular to said wall, spaced ratchets on said shaft, and means controlled by said electromagnets for actuating said ratchets.

7. In combination, a support formed with a horizontal upper edge and having an opening below said edge, and a screw threaded vertical opening extending down from said edge at right angles to the first opening and communicating therewith, an electromagnetic unit comprising a frame supporting an electromagnet and having a pin received within said first opening, said pin having a conical opening therein registering with the screw threaded opening, and a screw screwed within said screw threaded opening and having a conical end received within the conical opening of said pin, an insulating plate on said unit at substantially the level of said edge of said support, and adjacent thereto, said plate being formed with openings, the wires of said electromagnetic unit being flexible and passing individually through the openings in said plate, terminals on the ends

of said wires, terminals fixed to the upper edge of said support and insulated therefrom, substantially aligned with the openings in the insulating plate, whereby the terminals on the support and the corresponding terminals on said wires are disposed side by side, and cooperating, quickly detachable attachment means accessible from the top for attaching the terminals on the wires to the terminals on said support, said attachment means being detachable without removing the unit from the support.

8. In combination, a support formed with a horizontal upper edge, and having an opening below said edge, and a screw threaded vertical opening extending down from said edge at right angles to the first opening and communicating therewith, an electric unit comprising a frame, a pin on the frame received within said first opening, said pin having a conical opening therein registering with the screw threaded opening, a screw screwed within the screw threaded opening and having a conical end received within the conical opening of the pin, an insulating plate on said unit at substantially the level of the straight edge of said support and adjacent thereto, an insulating plate on the upper edge of said support disposed in substantially a single plane with the first insulating plate, said first insulating plate being formed with openings, the wires for said unit being flexible and passing individually through said openings in said first insulating plate, terminals on the ends of said wires, terminals fixed to said second insulating plate and substantially aligned with the openings in the first insulating plate, whereby the terminals on said second insulating plate and the corresponding terminals on said wires are disposed side by side, and cooperating, quickly detachable attachment means accessible from the top for attaching the terminals on the wires to the terminals on the second insulating plate, said attachment means being detachable without removing the unit from the support.

BENJAMIN COOPER.

45
